UNITED STATES PATENT OFFICE

102,865

DESIGN FOR A SIPHON BOTTLE OR SIMILAR ARTICLE

McClelland Barclay, New York, N. Y.

Application June 6, 1936, Serial No. 63,072

Term of patent 7 years

To all whom it may concern:

Be it known that McClelland Barclay, a citizen of the United States and resident of New York, in the county of New York and State of New York, has invented a new, original, and ornamental Design for a Siphon Bottle or Similar Article, of which the following is a specification, reference being had to the accompanying drawing, forming part thereof, in which,

Fig. 1 is a side elevation illustrating a siphon bottle embodying my design; and

Fig. 2 is a top plan view thereof.

I claim:

The ornamental design for a siphon bottle or similar article substantially as shown.

McCLELLAND BARCLAY.
